UNITED STATES PATENT OFFICE.

JOSEPH APPLIN, OF PHILADELPHIA, PENNSYLVANIA, ASSIGNOR TO THE
HALE & KILBURN MANUFACTURING COMPANY, OF SAME PLACE.

CAR-SEAT.

SPECIFICATION forming part of Letters Patent No. 561,153, dated June 2, 1896.

Application filed January 24, 1895. Serial No. 536,055. (No model.)

To all whom it may concern:

Be it known that I, JOSEPH APPLIN, of the city and county of Philadelphia, State of Pennsylvania, have invented an Improvement in 5 Car-Seats, of which the following is a specification.

My invention has reference to car-seats; and it consists of certain improvements which are fully set forth in the following specification and shown in the accompanying drawings, which form a part thereof.

My improvements comprehend certain features in reversible car-seats whereby the construction is made exceedingly simple and durable.

In carrying out my invention I provide a reversible seat-frame having the back and seat portion similar, so as to be interchangeable, and this frame I pivot upon supporting 20 pivoted bars, which may, if desired, constitute a frame, and the seat-frame I connect with the main frame of the car or car-seat by means of a suitable movable guide device, whereby in the act of reversing the seat it 25 is guided upward upon the pivoted arms or frame and caused to be reversed by the action of the movable guide device. In this manner the main weight of the seat-frame in the act of reversing is supported upon the pivoted bars 30 or frame, thus reducing the friction of reversing the seat to a minimum. The construction, furthermore, is exceedingly simple and not liable to get out of order.

My invention will be better understood by 35 reference to the accompanying drawings, in which—

Figure 1 is a sectional elevation, on line xx of Fig. 2, of a car-seat embodying my invention. Fig. 2 is a front elevation of my improved car-seat. Fig. 3 is a plan view showing a portion of a street-car where the seats 40 extend entirely across the car; and Fig. 4 is a plan view showing an adaptation of my improved seat to a car when the seats extend 45 only part way across, so as to leave an aisle.

A is the main frame of the car-seat.

B is the seat-frame proper and is provided with two portions C C of similar construction, one of which constitutes the seat and the other 50 the back, and vice versa. The seat-frame B is pivoted at I to the pivoted frame G, ful-

crum at H in the main frame A. The fulcrum H is low down, so as to move the top of the frame at the pivots I with as small an arc or curvature as possible. The seat-frame 55 B is provided at the ends with the arms D, which are provided with slots d, extending diagonally, as shown in Fig. 1. A guide-pin E, secured to the main frame, projects through or into the slots d, so as to guide the arms D 60 in the act of reversing the car-seat.

F are lugs or supports from the main frame, designed to support the seat-frame when in its extreme positions. It is evident that the frame G may be solid or open, as 65 shown, and may, if desired, be formed of the two end bars without intermediate connections, though the latter is preferred.

To reverse the car-seat, it is only necessary to lift upward on the forward part of the seat 70 portion, which action will cause the frame G to swing to the right and at the same time raise the seat-frame B. The guide-pin E acts as a fulcrum simultaneously with its guiding function and permits the seat-frame to be 75 turned about it, so as to bring the other portion C down upon the supports F F, while the parts C, formerly acting as the seat proper, rise to constitute the back. In this manner the seat is readily reversed and but small 80 friction is produced between the several moving parts, thus permitting the seat to be reversed with the smallest amount of labor.

My improvement has particular advantage 85 in light car-seats, such as are employed in street-railway cars, and especially those which extend entirely across the car, as indicated in Fig. 3. I, however, do not limit myself to any particular use of my improved seat, as it may be employed in steam-cars as well as 90 street-cars. It is also evident that, if desired, the parts C C may be upholstered, though commonly they will be employed with slat-work, as shown.

I do not confine myself to the minor details, 95 as they may be modified without departing from the principles of my invention.

Having now described my invention, what I claim as new, and desire to secure by Letters Patent, is—

1. A reversible car-seat composed of a unitary seat and back arranged at an angle with

reference one to the other and provided at its ends with arms having a pin-and-slot connection with a stationary part, and a rocking frame pivoted at one end to the unitary seat and back at the junction of the two parts and at the other end to the floor or stationary frame, whereby the said rocking frame and pin-and-slot connection will permit the said unitary seat and back to be shifted and when shifted will cause it to be reversed to change the relative position of the parts constituting the seat and back portions.

2. A reversible car-seat composed of a unitary seat and back arranged at an angle with reference one to the other and provided at its ends with arms having a pin-and-slot connection with a stationary part, and a rocking

frame pivoted at one end to the unitary seat and back at the junction of the two parts and at the other end to the floor or stationary frame, whereby the said rocking frame and pin-and-slot connection will permit the said unitary seat and back to be shifted and when shifted will cause it to be reversed to change the relative position of the parts constituting the seat and back portions, and supports F, F, on the stationary frame for supporting the seat portion at the front and back.

In testimony of which invention I have hereunto set my hand.

JOSEPH APPLIN.
